ASH TRAY

Matthew M. Berman, 363 Highland St.,
Newtonville, Mass.

Filed Jan. 9, 1964, Ser. No. 78,133

Term of patent 7 years

(Cl. D85—2)

FIG. 2

FIG. 3

FIG. 4

FIG. 1

FIG. 1 is a perspective view of an ash tray showing my new design;

FIG. 2 is a partial sectional view taken on line 2—2 thereof, on an enlarged scale;

FIG. 3 is an elevational view of the cigarette rest portion thereof; and

FIG. 4 is a top plan view of the cigarette rest portion. The essential features of the design are shown in full lines.

I claim:

The ornamental design for an ash tray, substantially as shown and described.
